Fig. 2

Fig. 4

Fig. 5

FIG. 1 is a top plan view of a reed for a reed switch showing my new design;

FIG. 2 is a front side elevational view thereof;

FIG. 3 is a right side elevational view thereof;

FIG. 4 is a top plan view of a modified form of the reed described in FIG. 1 showing my new design; and

FIG. 5 is a right side elevational view thereof.

The bottom plan views opposite to the top plan views of FIGS. 1 and 4 are identical to these respective figures. The left side and rear elevational views of the reed shown in FIGS. 1 and 4 are identical to FIG. 2. The tongues of FIGS. 1 and 4 include areas on either side thereof concavely depressed from the planar surface.

I claim:

The ornamental design for a reed for a reed switch, as shown and described.
